(57) **CLAIM**

The ornamental design for a cooling eye mask, as shown and described.

DESCRIPTION

FIG. 1 is a front perspective view of a cooling eye mask showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a plan view thereof; and,

FIG. 8 is a bottom view thereof.

The broken lines in the figures illustrate stiches and form a part of the claimed design.
